UNITED STATES PATENT OFFICE.

SAMUEL H. PAGE, OF STRATFORD, CONNECTICUT, ASSIGNOR TO THE AMERICAN FABRICS COMPANY, A CORPORATION OF CONNECTICUT.

DESIGN FOR LACE.

Application filed February 4, 1926. Serial No. 16,398. Term of patent 3½ years.

To all whom it may concern:

Be it known that I, SAMUEL H. PAGE, a subject of the King of Great Britain, residing at Stratford, county of Fairfield, State of Connecticut, have invented a new, original, and ornamental Design for Lace, of which the following is a specification, reference being had to the accompanying drawing, forming part thereof.

The figure is a plan view of a piece of lace showing my new design.

I claim:

SAMUEL H. PAGE.
